ALARM MECHANISM

William E. Procter, Baltimore, Md.

Application March 29, 1941, Serial No. 384,386

8 Claims. (Cl. 122—451)

This invention relates to alarm mechanisms and has for its principal object the provision of a marine gauge board alarm, the instruments of which are pneumatically controlled by the water level in the boiler.

A further object of the present invention is to provide a pressure regulator in which the sampling pipe extends directly into the boiler drum whereby the device is suited for marine installations.

A still further object of the invention is to devise a marine regulator governed by the water line in the boiler and suited to use wherever the pressures run relatively high and there is a rolling of the support, both of which cause conditions under which the normal land regulator is quite unsatisfactory or even inoperative.

Marine regulators of the general type illustrated herein depend for successful operation upon a constant escape of steam or water from the boiler. It is one object of the present invention to prevent the loss of this water and in so doing to save the appreciable number of B. t. u.'s in the water heretofore wasted. Likewise, while low and high water and pressure have been recorded on gauge boards in the engine rooms of ships these control boards have been heretofore operated by an electrical relay. In the present invention, the steam and water pressure is conducted directly to the pressure gauge and to a pressure switch adjacent the red light or the warning horn or both signals.

In the drawing:

Figure 1 is a diagrammatic assembly view showing the regulator connecting with an alarm mechanism and also with a feed water control valve.

Figure 2 is an enlarged detail of the regulating element.

Figure 3 is a side elevation of the gauge board.

In the drawing the numeral 10 represents the shell of a boiler drum having a normal water line at 11. A sampling pipe 12 extends approximately an inch below the normal water line as in land practice with this sharp distinction, however, that in the present case the sampling pipe 12 extends into the drum or boiler, whereas in land practice the invariable custom is to have the sampling pipe outside of the drum, usually parallel to the gauge glass. The sampling pipe may be in two or more parts connected by the usual couplings and it preferably passes directly through the dry pipe illustrated as a circular cross-section just below the top of the boiler drum 10.

The lower end 14 of the sampling pipe is open and in the side there may be a number of openings such as 15, usually one at the water line and two above the water line, although in many cases I find that I must space the openings quite high above the water line because of the extreme changes in the level of the water on shipboard

due to many different conditions of which the rolling of the ship is but one. The sampling pipe extension 16 may be threaded as at 17 into the body of the valve preferably below the shut-off connection 18 which is required when it is necessary to remove the inlet orifice 19 for any purpose as for example when this is blocked by a bit of scale. The chamber 20 communicates with the feed water control valve 21 and the instrument board 22 through the connection 23 while the connection 24 leads through the pipe 25 to the filter tank or heater thus providing a closed circuit for the water and steam which passes through the valve. The outer orifice 27 like the inlet orifice 19 is readily removable for replacement or cleaning.

The pipe 28 leading from connection 23 carries the pressure directly to the feed water control valve 21 or other instrumentality as well as to the instrument board, being separately connected with the control valve pressure gauge 30 and the commercially obtainable pressure switches 31 and 32 operating respectively the electric lamp 33, preferably a warning red color, and the siren or other alarm mechanism 35 to make an audible signal in case the visible signal 33 is not immediately noted, for this purpose being set to respond to a greater variation from the normal water line than are the lamp controlling pressure switches, that is, the switch 31 is set to act at one chosen pressure and the pressure switch 32 for the horn is set to go into action at a still lower pressure.

The operation of the apparatus has nothing to do with steam pressure, but is based solely on the fact that the sampling pipe scums the surface of the water, having a constant flow through it. The pressure in the drum 10 would be 450 pounds as a general rule. Because of the small orifice in the plug 19, the pressure in chamber 20 would only be about one-fifth that great. If, by any chance, the water level was very low and the fluid passing through the sampling pipe were dry steam, this could about as readily flow out the relatively larger orifice in 27 as it could flow into the smaller orifice in 19; hence the pressure in chamber 20 would be a minimum.

If, however, and this is usually the case, the fluid passing up the sampling pipe 12 is wet, the friction in passing through the exit orifice in plug 27 will be sufficiently great to build up a very substantial pressure in the chamber 20, about 90 pounds for example. As will readily be understood, when the superheated water passes thru the orifice in 19, the liquid will evaporate in part because of the much lower pressure in chamber 20 than in the drum 10. The total quantity of constant flow is reasonably small because of the tiny size of the orifice in 19 which restricts the discharge from the high pressure

side. Even with such a small flow the mixture of steam and water fills chamber 20 and is actively in motion because of the force of the jet entering thru 19. The pressure does not build up in chamber 20 (unless the ratio of the steam and water entering changes) because of the larger bore of the orifice in the exit plug 21. A normal ratio of orifice areas is one to five.

The pipe 28 and its branches are always full of water, never anything else. This water transmits whatever pressure exists in chamber 20. If the pressure in chamber 20 is at a minimum due to the presence of dry steam the pressure transmitted by the water column in pipe 28 is a minimum. If the water is high, chamber 20 is itself filled with water and the pressure is maximum. Thus it will be seen the steam pressure has nothing whatever to do with the pressure that may exist in chamber 20.

When the water level is unduly high, pressure is transmitted to the feed water control valve 21 which thereupon closes all flow to the boiler. When the water level is low, dry steam enters the bottom 14 of the sampling pipe and as it passes through the successively larger orifices 19 and 21, the pressure drop is much greater and consequently the pressure in pipe 28 is much less than if the sampling pipe extension 16 were filled with water. Thus with low water the spring of the feed water control valve 21 is too weak to hold closed the feed water control valve but the pressure switches 31 and 32 which are set to operate on decrease of pressure both act, one to flash the red light 33 and the other to sound the horn or siren 35. If desired a humidostat may be placed in the pipe 25 to shut off fuel when the water level drops sufficiently to cause the alarm mechanism to operate.

What I claim is:

1. In a marine boiler regulator, a pressure transmitting device responsive to the water level in the boiler, an instrument board located at a distance from the boiler and said device means including a column of liquid connecting the instrument board with said device, a visible indicator and an audible indicator on said board, pressure switches for operating the indicators at different pressures, whereby changes in pressure in the device as the water level in the boiler fluctuates are transmitted hydraulically from the device to the board and one indicator will be operated at one water level and the other will operate at a different water level.

2. In a marine regulator, a pressure vessel, a regulating element outside of said pressure vessel, a sampling tube extending from the regulating element to a point within the vessel and slightly below the normal water line and having a plurality of holes therein at different levels, said regulating element having an open discharge means and a smaller inlet means, whereby the pressure in the vessel causes a constant flow through said holes in the sampling pipe and the pressure within the regulating means is responsive to changes in the water level of the pressure vessel.

3. In a marine regulator, a cylindrical pressure vessel, a regulating element located outside of the pressure vessel, an instrument board, hydraulic means including a column of liquid transmitting pressure from the regulating element to

the instrument board, and a sampling tube extending from the regulating element into the pressure vessel, radially of same to convey a constant flow of fluid from the pressure vessel to the regulating element.

4. The device of claim 2 in which the sampling tube has an open end beneath the normal water line and has an opening at a distance above the normal water level of at least one-fourth of the radius.

5. In a marine installation, a cylindrical pressure vessel, a regulating element including a chamber having a restricted inlet orifice, a less restricted exit orifice and a third orifice between the other two, means connecting the third orifice to a control device, means connecting the inlet orifice with the interior of the vessel, and means connecting the exit orifice to a return to the pressure vessel, whereby the fluid constantly passing from the vessel thru the regulating element is returned to the pressure vessel with a consequent saving in the heat value of such returned water.

6. A marine boiler installation including a pressure vessel, a passageway from the vessel including an open-ended sampling tube within the vessel and a pressure chamber having a reduced entrance orifice and a less reduced exit orifice, and means governed by the pressure in said chamber for controlling the flow of water to said vessel, said sampling tube extending thru a point where the normal waterline meets a vertical plane thru the center of the vessel and having an opening above its lower open end to provide for entry of splashed water, steam and scum from the steam space in the vessel and said open end of the tube extending below the normal water line, whereby the normal flow of fluid through the pressure chamber will be wet steam and the flow of fluid thru the pressure chamber will be relatively dry steam when the water level falls well below the open end of the sampling tube.

7. In a marine boiler installation, a drum to contain water and steam under high pressure, a chambered body above the vessel, a sampling pipe extending from the body into the vessel to a point slightly below the normal water line, a restricted port between the pipe and the chamber of the body, a larger port leading from the chamber to provide a constant flow of fluid from the drum through the chamber, a third port opening into the chamber between said ports and larger than either of the other ports, and a pressure responsive instrument hydraulically connected to the third port so as to respond to changes in the water level of the vessel as reflected by changes in pressure in the chamber due to the varying amounts of water in the steam which passes thru the chamber as the water level raises and falls with respect to the lower end of the sampling pipe.

8. In a marine boiler installation, a drum, a scumming sampling pipe extending vertically into the drum at about its center line, with the bottom end of the pipe below the normal water line, said pipe having a plurality of side openings above the normal water line, and means for restricting the flow through the upper end of the pipe but providing a constant flow therethru.
